(57) **CLAIM**

I claim the ornamental design for a combination paint cup with brush holder and roller wall, as shown and described.

DESCRIPTION

FIG. 1 is a front perspective view of a combination paint cup with brush holder and roller wall, showing my new design;
 FIG. 2 is a rear perspective view thereof;
 FIG. 3 is a front elevational view thereof;
 FIG. 4 is a rear elevational view thereof;
 FIG. 5 is a left-side elevational view thereof, the right-side elevational view being a mirror image thereof;
 FIG. 6 is a top plan view thereof;
 FIG. 7 is a bottom plan view thereof; and,
 FIG. 8 is a cross-sectional view thereof, taken along line 8-8 of FIG. 6.
